UNITED STATES PATENT OFFICE.

MORTON G. BUNNELL, OF CHICAGO, ILLINOIS, ASSIGNOR TO FREDERICK C. AUSTIN, OF CHICAGO, ILLINOIS.

RAILROAD TRENCH-MACHINE.

1,158,979.

Specification of Letters Patent.

Patented Nov. 2, 1915.

Application filed April 12, 1909, Serial No. 489,307. Renewed May 23, 1913. Serial No. 769,500.

To all whom it may concern:

Be it known that I, MORTON G. BUNNELL, a citizen of the United States of America, and resident of Chicago, Cook county, Illinois, have invented a certain new and useful Improvement in Railroad Trench-Machines, of which the following is a specification.

My invention relates to excavating machines, and more particularly to excavators 10 adapted for trenching.

Machines of this kind are employed in making ditches for tile or conduit or the like, and are capable of cutting a trench in the ground as the machine moves slowly 15 forward.

Generally stated, the object of my invention is to provide an improved form of trenching machine, of the above general character, and for the general purposes 20 specified.

A special object is to provide an excavator for use in laying conduits, or for other purposes, as by cutting a trench along the side of a railroad track, and to provide an excavator which will be capable, therefore, of traveling along the track, in the manner of an ordinary flat car, and which will furnish power to operate the trenching device which overhangs the side of the machine to an extent sufficient to form the trench for the conduit at a suitable distance from the side of the track.

With a machine embodying the principles of my invention, a trench or ditch, for any desired purpose, can be dug along a railroad track, by simply running the excavator car along the rails thereof, the car being preferably self-propelling.

To the foregoing and other useful ends, 40 my invention consists in matters hereinafter set forth and claimed.

In the accompanying drawings—Figure 1 is a side elevation of an excavator embodying the principles of my invention, showing 45 the same in operation, whereby a trench or ditch is being dug at the side of a railroad track upon which the excavator travels like an ordinary flat car, except that it is self-propelling. Fig. 2 is a rear elevation of the said machine. Fig. 3 is a plan of the same.

As thus illustrated, my invention comprises a flat car A having the usual car wheels B, whereby it is adapted to travel upon the rails C of the track. The excavating device D is carried at the side of the

car, and is adapted to form a trench at a suitable distance from the side of the track. The said device consists of an endless belt d having teeth or cutters d' distributed over the surface thereof, and longer teeth d² at the sides thereof, whereby the trench cut is a little wider than the belt. The said belt travels over wheels d³ and d⁴ at the upper and lower ends of the swinging excavating device. These wheels are mounted upon shafts d⁵ and d⁶, as shown. The belt travels between a pair of sides or boards d⁷, which latter are carried on the shaft d⁵. The shaft d⁶ is carried in the lower ends of these sides d⁷. The shaft d⁵ is supported in bearings 65 carried on a frame d⁸ which overhangs the side of the car. A bail d⁹ is pivotally secured to the sides of the excavating or cutting device, and has its upper end pivotally connected with the crank arm d¹⁰ on the 70 rock shaft d¹¹ carried on the car. By means of a lever d¹² this shaft d¹¹ can be rocked to raise and lower the excavating device D, by swinging the lower end of the same up and down about an axis coincident with the 75 shaft d⁵. The forward or under side of the belt d travels up and the top or rear side travels down.

A shield E, adjustably carried on the inner side of the excavating device D, prevents 80 the excavated dirt from crowding over onto the track. The adjustability of the said shield can be obtained in any suitable manner. A deflector or scraper F, adjustably secured to the outside of the excavating device, and disposed obliquely to the line of travel, with its outer end slightly to the rear of its inner end, serves to throw the dirt 85 away from the ditch or trench. The adjustability of said scraper is obtained by bolt holes f in the side d⁷, adapted to engage the bolts f¹ and f² of the arms f³ and f⁴ of the scraper. The arm f⁴ has a slot f⁵ for the bolt f², whereby an angular adjustment of the scraper about the bolt f² may be had. Similar adjusting means can be used for the shield E. Thus all excavated dirt is left in a ridge outside of the trench. The said shield E cooperates with the cutter to push and crowd the dirt to the outer side of the trench. 100 But any suitable means may be employed for mounting said shield and scraper.

Upon the car is an engine or motor G of any suitable character. The shaft g, which extends transversely of the car, is gear con- 110

2
nected with said engine or motor in any suitable manner. The car wheels are driven from this shaft, by any suitable transmission. The shaft d^5 is also driven from the 5 shaft g , by any suitable means. Clutches X and Y may be used, respectively, for controlling the transmission of power to the car wheels and the excavating device. Thus the 10 car can be run without operating the excavating device, and said device can be operated without communicating power to the car wheels.

The mode of operation is as follows: The 15 device D is lowered to the ground, and the car started ahead. The power is also connected with the belt d . Thus the said belt operates as the car moves along. In this way the device D cuts a trench or ditch as the car moves along the track. The dirt cut 20 and carried up by the belt is pushed forward, and then outward by the deflector or scraper F, as explained. The depth of the trench or ditch is regulated by the lever d^{12} , which has means for locking it in different 25 positions. A segment H can be employed for this purpose, as shown.

When the car is traveling from place to place, the excavating device D is drawn up and remains idle at the side of the excavator. The car can be used for carrying men 30 and materials.

Thus I provide a self-propelling excavator capable of traveling upon an ordinary track, and capable of rapidly and economically 35 and effectively cutting a trench at the side of the track, whereby tile or conduit may then be laid in the ordinary manner.

Considered in connection with the kind of work shown, the device D is in the nature of 40 a trench cutter carried at the side of the car. It may also be used for making ditches for drainage purposes. By varying the shape of the said device, various kinds of ditches can be dug. The endless belt can also be varied, 45 by suitable modification, for carrying the dirt upward without discharging it directly onto the ground. The dirt might be carried upward and delivered to the other side of the car, or onto the car. For these reasons, 50 I do not limit myself to use of the said devices for trenching. Means, of any suitable character, are provided for varying the speed of the car, depending upon the kind of soil or the character of the work. For example, 55 the ratio or proportion of the sprocket gearing Z, by which the engine drives the car wheels, may be varied or changed for different kinds of work, or for different kinds of soil. The speed of the car will also be 60 dependent, more or less, upon the depth at which the device D is operating. Clutches and gearing, however, are so common that no further explanation is necessary.

Obviously, means can be provided for 65 varying the distance of the device D from

the side of the track, or from the side of the car. This can be done by sliding the wheel d^8 on the shaft g , and by sliding the arm d^{10} on the shaft d^{11} , said shafts being made long enough for this purpose. Or other suitable means of adjustment can be used for 70 this purpose.

What I claim as my invention is:

1. In an excavator, means for cutting a 75 trench at one side of the road bed, comprising a suitable traveling body, a trench cutter disposed at one side thereof, a shield for preventing the dirt from crowding inward, and a scraper for throwing the dirt outward, the cutter running between the shield and scraper. 80

2. In an excavator, means for cutting a 85 trench at one side of the road bed, comprising a suitable traveling body, a trench cutter disposed at one side thereof, a shield for preventing the dirt from crowding inward, and a scraper for throwing the dirt outward, the 90 cutter running between the shield and scraper, said trench cutter consisting of an endless belt with cutters thereon, mounted 95 on said body, said cutter operating to discharge the dirt carried upward thereby on the surface of the ground.

3. In an excavator, means for cutting a 95 trench at one side of the road bed, comprising a suitable traveling body, a trench cutter disposed at one side thereof, mounted to move up and down, a shield for preventing the dirt from crowding inward, and a 100 scraper for throwing the dirt outward, the cutter running between the shield and scraper, said scraper being suitably mounted on the outer side of said trench cutter, movable up and down therewith.

4. In an excavator, means for cutting a 105 trench at one side of the road bed, comprising a suitable traveling body, a trench cutter disposed at one side thereof, a shield for preventing the dirt from crowding inward, a scraper for throwing the dirt outward, the 110 cutter running between the shield and scraper, and means for varying the angle of said trench cutter, about an axis extending transversely of said body, serving to hold 115 said cutter against rising while in working position between said shield and scraper.

5. In an excavator, means for cutting a 120 trench at one side of the road bed, comprising a suitable traveling body, a trench cutter disposed at one side thereof, means whereby said cutter may be raised and lowered, a shield for preventing the dirt from crowding inward, and a scraper for throwing the dirt outward, the cutter running between the shield and scraper, said shield and scraper being mounted on said trench cutter, movable up and down therewith.

6. In an excavator, a traveling body, a 125 trench cutter carried thereby, at one side thereof, for cutting a trench at one side of 130

the road bed, having means to discharge the dirt on the ground ahead of the trench, and a shield for preventing the loose dirt from crowding over the road bed, disposed inside 5 of said cutter, secured thereto, and movable therewith about a horizontal axis, coöperating with the trench cutter to keep all of the dirt at the outer side of the trench.

7. In an excavator, a traveling body, a trench cutter carried thereby, at one side thereof, for cutting a trench at one side of the road bed, operating to discharge the dirt on the ground ahead of the trench, means for raising and lowering the cutter, and a 15 scraper for pushing the dirt away from the outer side of the trench, secured to said cutter movable up and down therewith.

8. In an excavator, a traveling body, a trench cutter carried thereby, at one side thereof, for cutting a trench at one side of the road bed, having means to discharge dirt on the ground ahead of the trench, and a scraper disposed in position for pushing the dirt away from the outer side of the 20

trench, arranged at the outer side of said cutter, and bodily movable therewith about a horizontal axis, means to propel the excavator forward, mechanism for operating said cutter during the forward travel of the excavator, and means to secure the scraper 30 to the side of the cutter.

9. In an excavator, a traveling body, a trench cutter carried thereby, at one side thereof, for cutting a trench at one side of the road bed, having means to discharge the dirt on to the ground ahead of the trench, means for operating said cutter and means whereby all of the dirt brought up to the surface by said cutter is pushed and crowded to the outer side only of the trench, together 35 with means for propelling said body while the cutter is operating.

Signed by me at Chicago, Illinois, this 5th day of April, 1909.

MORTON G. BUNNELL.
